UNITED STATES PATENT OFFICE.

HARRISON D. SPANGLER, OF RUSHVILLE, INDIANA.

PLOW-HANDLE.

SPECIFICATION forming part of Letters Patent No. 311,790, dated February 3, 1885.

Application filed May 26, 1884. (No model.)

To all whom it may concern:

Be it known that I, HARRISON D. SPANGLER, of the town of Rushville, county of Rush, and State of Indiana, have invented certain new and useful Improvements in Plow-Handles, of which the following is a specification.

The object of my said invention is to produce a cheap, efficient, and durable plow-handle or other handle having a crooked hand-piece. This object is accomplished by making a cast hand-piece, which extends down as far as the handle is crooked, and adapting it, in the manner hereinafter more particularly described and claimed, to be securely fitted to the straight part of said handle, which is preferably formed of wood.

Referring to the accompanying drawings, which are made a part hereof, and on which similar letters of reference indicate similar parts, Figure 1 is a perspective view of that portion of a handle which embraces my invention; Fig. 2, a central longitudinal section through the same, and Fig. 3 a transverse sectional view looking toward the right from the dotted line *z z* in Fig. 2.

In said drawings, the portions marked A represent the main handle, and B the hand-piece. The handle A is in most particulars of an ordinary formation, and is of a length 30 to extend from the plow up to that point where it is usually bent to form the hand-piece. Its top end is tenon-shaped, and is slightly tapered on its top and under sides from the shoulders *a* of the tenon to the end, and I 35 leave a short space between the end of the hand-piece and said shoulders *a* after said hand-piece has been driven onto said tenon, to allow the two parts to be tightened up if the hand-piece should afterward become loose 40 by reason of shrinkage or wear. The hand-piece B is preferably cast from malleable iron; but any other suitable metal may be used, if desired. Its lower end is formed into a socket, which is adapted to fit onto the tenon-shaped 45 end of the wooden part of the handle. Said socket is an open-sided socket, its top and bottom parts being flared apart slightly to fit to the corresponding taper of the tenons. By

reason of having the socket open-sided its top and bottom parts are adapted to be sprung 50 either apart or toward each other in putting it onto the tenon, and can thus be more easily fitted and securely clamped thereto. It is held in position by a bolt, *b*, which extends down through said socket near its end and the tenon. 55 By this bolt the parts of the socket through which said bolt passes can be drawn very tightly against the end of the handle, and a very secure fastening thus effected. The holes in the socket through which the bolt *b* passes 60 are elongated to allow the hand-piece to be driven onto the handle farther if it should become loose, and thus tightened without forming another bolt-hole in the tenon. Said hand-piece is preferably cast hollow, and is thus 65 made light and cheap. Open spaces along the sides may also be formed, if desired, as shown. By the use of this invention the expense of forming the hand-pieces on the end of the handles is saved, and a durable and efficient handle 70 is produced.

I am aware that hand-pieces have heretofore been provided for handles; but I am not aware that any such hand-piece has been produced embodying the features herein claimed. 75

Having thus fully described my said invention, what I claim as new, and desire to secure by Letters Patent, is—

The combination of a plow-handle, A, having a tapering tenon upon its upper end, and 80 a metallic hand-piece, B, having a tapering socket upon its lower end, adapted to fit over said tapering tenon and elongated bolt-holes, and the bolt *b*, adapted to pass through said tenon and said bolt-holes and secure said 85 handle and hand-piece together, substantially as shown and described.

In witness whereof I have hereunto set my hand and seal, at Rushville, Indiana, this 21st day of May, A. D. 1884.

HARRISON D. SPANGLER. [L. S.]

In presence of—

JOHN W. STUDY,
SAMUEL TEMPLIN,
J. F. COONS.
